US0D1101439S

(12) United States Design Patent (10) Patent No.: US D1,101,439 S
(45) Date of Patent: * Nov. 11, 2025

(54) CHAIR

(71) Applicant: Ningbo Yousheng International Trade Co., Ltd., Ningbo (CN)

(72) Inventor: Yongzhen Chen, Zhejiang Province (CN)

() Term: 15 Years

(21) Appl. No.: 35/523,027

(22) Filed: Oct. 31, 2024

(80) Hague Agreement Data

Int. Filing Date: Oct. 31, 2024

Int. Reg. No.: DM/241893

Int. Reg. Date: Oct. 31, 2024

Int. Reg. Pub. Date: Nov. 22, 2024
